CHARLES O. YALE, OF ROME, NEW YORK, ASSIGNOR TO HIMSELF AND
THEODORE W. MAHLER, OF SAME PLACE.

Letters Patent No. 78,908, dated June 16, 1868.

IMPROVEMENT IN CORN-HUSKER.

The Schedule referred to in these Letters Patent and making part of the same.

TO ALL WHOM IT MAY CONCERN:

Be it known that I, CHARLES O. YALE, of Rome, Oneida county, New York, have invented a new and improved Corn-Husker; and I do hereby declare that the following is a full, clear, and exact description of the construction and mode of operation of the same, reference being had to the annexed drawings, making a part of this specification, in which—

Figure 1 is a sectional view through the centre of the machine.

Figure 2 an end view.

Figure 3 represents the back side,

Figure 4 the front side, and

Figure 5 a side view of the slide and connected parts.

A represents the frame.

B, the table.

C, the upper roller for passing the stalks.

C¹, a pulley on the back end of C.

D, the lower roller for passing the stalks.

D¹, driving-pulley or crank.

D², endless cord.

D³, pulley on back end of D.

D⁴, a pulley on a pin in the frame.

D⁵, pulley-block.

D⁶, a spring.

D⁷, fulcrum and guide.

E E, bearings for the rollers C and D.

E¹ E¹, rubber springs above axis of C.

F, reel.

F¹ F¹, rods.

F², guide.

F³, pulley on back end of shaft.

G, hopper.

H, conveyer.

H¹, spring-arm.

H², spring-catch or stop.

I, slide.

I¹, driving-wheel of slide.

I², driving-pins.

I³, arm.

K, plate.

L L¹, husking-rollers.

L², India-rubber tubing on L¹.

L³, pinion on front of L¹.

L⁴ L⁵, pinions on back ends of L and L¹.

M M, pressure and rotating rings.

N, spurred gear on front of D, gearing into

N¹; a like gear on a pin in the frame giving motion to

N², the gear on front of shaft of reel, which gears into

N^3 , a gear like N , and which gears into
 N^4 , of like size, which has on its shaft a larger wheel,
 N^5 , which gears into L^3 .

The upper roller, C , may be of wood. It is much larger than the under one, D , and is set a little in advance of it. They are in bearings, E E , attached to the top of the back end of the frame, as seen in figs. 2 and 4. There are rubber or other proper springs, E^1 E^1 , over the axis of C , to allow it to accommodate itself to the cornstalks. The driving-pulley or crank D^1 is on the front end of the axis of D , and the upper roller, C , is driven by an endless cord, D^2 , passed around the pulleys D^3 , D^4 , and C^1 ; and the pulley-block D^5 , while the spring D^6 allows sufficient play to the cord to permit C to rise and fall according to the size of the cornstalks.

The fulcrum D^7 is under D , and is best formed of plate metal curved up in front of D , with its rear end extending to the top of the hopper.

In front of C and D , but a little lower, is the reel F . It has a central shaft, with two circular end plates, or may be cross-arms, and, say six rods, F^1 F^1 , and is driven by gearing N^2 , which receives motion from N . The rods F^1 F^1 press down the ears of corn against the fulcrum D^7 , and break them off, which fall into the hopper G at the back end of the machine, and under C and D .

From the hopper the ears of corn are taken up one by one, by the conveyer H , which is in form something like a water-wheel with buckets. Intermittent motion is given to it by the arm H^1 on the slide I , and it is kept from turning back by the catch or stop H^2 , attached to the frame A . The slide I is divided into two parts at its front end, one of which is on the inside, and the other on the outside of the wheel I^1 , which is on the shaft of N^4 and N^5 . On each side of I^1 are two pins, I^2 I^2 . One set push against the end of one division of the slide, and the other set engage in a notch on the other half and draw it back. Thus it moves twice each way for each revolution of the wheel.

Between the conveyer and husking-rolls is a plate, K , and directly over this plate is an arm, I^3 , attached to the slide.

The husking-rolls are two, L and L^1 . The front one, L , should be covered with India rubber, cloth, cord, or the like, and the other, L^1 , has an India-rubber tubing, L^2 , of much larger size than the roll itself, as seen in figs. 1 and 5. These rolls are made small, of about the size of D . L^1 should be somewhat less than the other, that the tubing may rotate regularly without slipping or being rubbed by L . Such difference will of course depend on the thickness of the tubing. L^1 has a pinion, L^3 , on its front end, which is driven by N^5 , and each has a pinion on the back end, L^4 L^5 , by which L is driven.

Directly over the husking-rolls is a series of rings, M M , on a small revolving horizontal shaft, in the form of pinion-wire, driven by a cord and pulley, connected with the pulley on the back end of the reel F^3 , as seen in fig. 3. These rings M are toothed on the inside and outside, and as the shaft revolves they are carried round with it. The outside teeth are like those of a slightly-indented circular saw. To give free motion to the rings, a disk is interposed between them, as seen in fig. 2.

The operation of the corn-husker will be obvious from the description already given. The stalks are laid on the table B with the butts against the rolls C and D , and the machine started by hand, horse, or steam-power, and the stalks are drawn in until the ear reaches the rolls. The greater size and forward position of the upper roll depress the point of the ear so that the reel in its revolution will reach it and press the stem against the fulcrum D^7 , and break it off, and the stalk, now freed, passes over the back end of the fulcrum or guard beyond the machine, and the ear, guided by F^2 , falls into the hopper, and thence into one of the buckets of the conveyer, and at each forward motion of the slide I , the arm H^1 will move up the ear one step. When it has passed over the top it will then fall over the arm I^3 , and on to the plate K , and the arm I^3 moved forward by the slide I , pushes it forward over K towards the husking-rolls and under the rings M M . The surface of K is pointed and rough, and so is the face of the arm I^3 . The latter holds the ear from turning, while the surface of K loosens the husk on the under side, which enables the husking-rolls the more readily to take hold of it. The husking-rolls now seize the husk, while the weight of the rings M presses evenly on the ear, and the outer teeth cause it to turn around, and the whole is readily removed. In the mean time another ear has been pressed forward by the arm I^3 , which forces out the husked ear, when the husk is removed from the second one, and it is forced out by a third one, and so on.

Instead of making the conveyer as described, it may be in any other convenient form, as an endless apron, and the motion may be continuous instead of intermittent. Instead of gearing as described, pulleys and belts, or cords or spurred wheels, with chains, may be used in the manner which will readily occur to the competent mechanic, and motion may be given to the slide I by a crank or other proper means, instead of in the manner described. The roll C may be of the same size as D , and it may also be directly over D , instead of being placed in advance of it. Instead of the reel being of the form described, it may be so made as to have an arm move forward and press off the ear, and then recede instead of having a rotary motion, and the arms F^1 may be covered with rubber or the like, to prevent injury to the corn.

Having thus described my invention, what I claim therein as new, and desire to secure by Letters Patent, is—

1. The rolls C and D , in either form as described, in combination with the reel F , or its equivalent, for the purposes mentioned.
2. The pulleys C^1 , D^3 , D^4 , and D^5 , endless cord D^2 , and spring D^6 , constructed and arranged substantially as described and for the purposes mentioned.
3. The conveyer H and arms H^1 and H^2 , constructed and arranged substantially as described, and for the uses and purposes mentioned.
4. The conveyer H and the husking-rolls L and L^1 , constructed and arranged substantially as described, and for the uses and purposes mentioned.

5. The rings M M, constructed and arranged substantially as described, and for the uses and purposes mentioned.

6. The plate K and the arm I³, constructed and arranged substantially as described, and for the uses and purposes mentioned.

7. The table B and the reel F, constructed and arranged substantially as described, in combination, for the uses and purposes mentioned.

C. O. YALE.
